UNITED STATES PATENT OFFICE.

JAMES COWGILL, OF LOWELL, MASSACHUSETTS.

LOOM.

SPECIFICATION forming part of Letters Patent No. 375,131, dated December 20, 1887.

Application filed March 7, 1887. Serial No. 229,958. (No model.)

To all whom it may concern:

Be it known that I, JAMES COWGILL, a citizen of the United States, residing at Lowell, in the county of Middlesex and Commonwealth 5 of Massachusetts, have invented a certain new and useful Improvement in Looms, of which the following is a specification.

My invention relates to looms for weaving; and it consists in the means, hereinafter described and claimed, of keeping an even tension on the warps, and of enabling the shuttle to be thrown by a less expenditure of power, and to steady the shuttle in its movement across the lay.

15 In the accompanying drawings, Figure 1 is an end elevation of so much of a loom as is necessary for the understanding of my invention, and my invention attached thereto; Fig. 2, a front elevation of part of the loom-frame, 20 the lay and its usual appurtenances, and a shuttle on said lay, the picker-sticks, picker-straps, picker-levers, the cams which operate them, the driving-pulley, the loose pulley, the dagger-rod, the warp-beam, and my improvements; Fig. 3, a side elevation of the beam-head gear, the gear on the friction-pulley, and the intermediate gear which connects said gears; Fig. 4, a section on the line $x-x$ in Fig. 1; Fig. 5, a section on the line $y-y$ in Fig. 1.

30 The frame A, lay B, its beam b, lay-shaft b', picker-sticks C C', the so-called "Stearns parallel motion" c, the shuttle-binders D D', their pivots d d', the shuttle-boxes E E', the warp-beam F, main shaft G, fast and loose pulleys 35 g g', cranks g'', connected by pitmen g''' to the lay, the cam-shaft H, provided with cams h h', picker-levers I I', provided with shoes i i' and pivoted at their rear ends to the frame A, and connected to the picker-sticks C C' by picker-straps J J', and the picker-strap rolls j j', are 40 all of the usual construction and operation.

In Fig. 2 the shuttle is represented as moving from right to left. Ordinarily the shuttle enters the shuttle-box against the resistance 45 of the binder, which is pressed backward toward the back of the shuttle-box by a stiff spring, and the shuttle is driven out of the shuttle-box by the picker (not shown) attached to the picker-stick, near the upper end of the 50 same, striking the end of the shuttle with a force sufficient to overcome not only the in-

ertia of the shuttle, but the friction of the shuttle-box and binder.

I dispense with the binder-spring and push the binder inward by means hereinafter described, and just previous to the striking of the shuttle by the picker I release the binder.

The picker-straps which connect the picker-sticks and their respective picker-levers pass under the rolls j j' in the usual manner, so that 60 when either picker-lever is raised in the usual manner by the revolution of the cam-shaft H its picker-strap draws the upper end of the picker-stick to which it is connected inward, or toward the middle of the lay, and throws 65 the shuttle before it out of one box and into the other. When the front end of the picker-lever falls, the picker-strap slackens and the upper end of the picker-strap is thrown outward by means of a spring, c', roll c'', and strap 70 c''' of the Stearns parallel motion.

On the rod K, which forms the pivot of each of the rolls j j', turns a balance or lever L L', the inner end of which lever reaches under a picker-lever, and to the outer end of 75 which is pivoted a roll, l, immediately below and in contact with the picker-strap. When the picker-stick is thrown outward, as above described, the roll l presses against the picker-strap and draws the picker-stick inward 80 slightly, out of contact with the outer end of the picker-stick slot, the picker-lever at this time resting upon the inner arm of said lever L. When the shuttle, after entering the shuttle-box, strikes the picker and drives it back 85 toward the end of the slot in which the picker-stick moves, the elasticity of the picker-strap serves to check the motion of the shuttle gradually, and finally to stop it, so that very little pressure need be applied to the binders, 90 which are intended to work so easily as to oppose but very slight resistance to the entrance of the shuttle into the shuttle-box, but serve to prevent the shuttle from rebounding. The

very slight pressure that is put upon the binders is caused by the pressure of the dagger-rod fingers M M', which, with the dagger-rod m and dagger m', are of the usual construction and turn in brackets m'' m'', secured to the lay in the usual manner. The lever L', pivoted 100 on the stud of the roll j', is precisely like the lever L. The dagger-rod m is provided with

two backwardly-projecting arms, N N', connected by cords n n' or wires to the inner arms of the balances or levers L L'. The arms N N' and the inner arms of the levers L L' are provided with a series of holes or notches, n² l², respectively, to enable the cords or wires which connect them to be adjusted nearer to or farther from their ends to vary the amount of the pressure of the dagger-rod fingers upon the binders, said pressure being caused by the weight of the picker-levers, which alternately rest upon the inner arms of the levers L L', connected, as above stated, to the arms N N' of the dagger-rod.

15 It requires less power to throw the shuttle when the binder presses lightly upon the shuttle, and I am enabled to attach the picking-strap nearer the top of the picker-stick, and thereby to throw the shuttle with less force 20 without substantially increasing the time required for the throw of the shuttle.

In order that the shuttle may not be retarded by the varying slackness of the warps, I find it necessary to keep the warps uniformly taut and the upper part of the shed 25 out of contact with the shuttle in the race.

The friction-wheel o is secured to and turns with the gear O, which engages the intermediate gear, O', which in turn engages the 30 beam-head gear O², the latter being secured to the head f of the warp-beam F in the usual manner. The motion of the friction-wheel is retarded by the brake P, which consists of a piece, p, concave in its under surface, and 35 provided at its ends with small rolls, p' p², to which are secured ratchets p³ p⁴.

A rope or cord, p⁵, secured to the rolls p' p², may be drawn more or less taut by turning 40 said rolls, which are prevented from turning backward by pawls p⁶ p⁷, pivoted on said piece p and engaging said ratchet.

The tension of the cord p⁵ is varied by winding or unwinding, to allow it to have a greater or less contact with the periphery of said friction-wheel, and thereby to create a greater or less friction thereon. The brake is provided 45 with an upward projection, p⁸, provided with a slot, p⁹, to allow the rod K to extend through said projection, and to allow said projection to rise and fall on said rod. The projection p⁸ and brake P are prevented from moving along on said rod K by nuts k' k² and check-nuts k² k³, which engage a screw-thread on said rod, but which are not turned up close 50 enough to the projection p⁸ to prevent the brake from rising and falling on said rod to vary the friction between the brake and the wheel, as hereinafter described. The rod K slides longitudinally in brackets a a' on the 55 frame A, so that the drawing of the warps from the warp-beam causes the gears O O' O² to revolve in the direction shown by the arrows marked on them, and causes the friction-wheel to revolve and by friction on the brake to slide 60 the rod K forward.

The rod K is provided with two fingers, k⁴ k⁵, provided with collars k⁶ k⁷, which surround

70 said rod and are adjustable thereon by means of set-screws k⁸ k⁹. When the rod K is moved endwise out of its normal position, one or the other of the fingers k⁴ k⁵ will be struck by the cam h, which operates one of the picker-levers, and the rod will be restored to position. The fingers k⁴ k⁵ are so arranged on the rod K as not to be struck by the cam h when the rod K 75 is in its normal position. The pressure, and consequently the friction, of the brake upon the friction-wheel may be varied by moving the weight Q on the lever q, the latter being pivoted at its front end at q' on a bracket, q², 80 secured to the frame A, said lever q having a downward projection, q³, which rests upon the top of the projection p⁸ of the brake p, the weight Q being placed at the outer or rear end of the lever q when the beam is full, and 85 afterward, as the beam is gradually emptied, being moved by hand toward the fulcrum q'. 85

It will be seen that the friction of the brake on the friction-wheel retards the motion of said wheel and of the gears O O' O², the first of said 90 gears being secured to said friction-wheel and the last, O², of said gears being secured to the head of the warp-beam, and therefore retards the motion of the warp-beam, and, by preventing the warps from being unwound too rapidly 95 from said beam keeps the warps in a proper state of tension and prevents the warps in front of the harnesses from sagging down onto the shuttle.

A sudden slackening or straining of the 100 warp may cause the brake and the rod K to move back or forth; but in the ordinary operation of the machine the front finger, k⁵, is not likely to be struck by the cam h. A sudden excessive strain on the warp-yarns would 105 rotate the beam and the gears O² O' O in the direction shown by the arrows and move the brake forward by the friction of the friction-wheel on said brake, and the yielding or forward movement of the brake would immediately relieve the strain on the warp-yarns, whereas if the brake were immovable some of the warp-yarns would be likely to be broken by such sudden strain.

When the improvements above described 115 are used, the shuttle is less liable to be thrown out of the race, because the upper part of the shed is held out of contact with it, and the shuttle is thrown with less force and with 120 greater steadiness, and for the same reasons 120 the warps are less likely to be broken out.

I claim as my invention—

1. The combination of the picker-sticks, the picker-levers, the picker-strap connecting said picker-sticks and picker-levers, the picker-strap rolls, the binders, the dagger-rod having fingers resting against said binders and provided with arms, the balance-levers, rolls on the outer ends of said balance-levers below said picker-straps, and cords or wires connecting the inner ends of said balance-levers and the arms of said dagger-rods, the inner arms of said balance-levers being arranged to 130 be struck by said picker-levers and to press

said dagger-rod fingers against said binders, the cam-shaft and its cams which operate said picker levers, as and for the purpose specified.

2. The combination of the picker-sticks, the 5 picker-levers, the picker-straps connecting said picker-sticks and picker-levers, the picker-strap rolls, the balance-levers, rolls on the outer ends of said levers below said picker-straps, the inner arms of said balance-levers 10 being arranged to be struck by said picker-levers to press the rolls pivoted to the outer ends of said balance-levers against said picker-straps and to take up the slack of said straps, and the cam-shaft and its cams which operate 15 said picker-levers, as and for the purpose specified.

3. The combination of the warp-beam provided with a gear, the friction-wheel provided with a gear, an intermediate gear engaging 20 each of said first-named gears, the brake provided with an upward projection slotted ver-

tically, as described, a rod passed horizontally through the slot in said projection, means, substantially as described, of causing said brake to move with the longitudinal motion of said 25 rod, fingers secured to said rod, the cam-shaft provided with a cam arranged between said fingers and adapted to revolve without striking said fingers when said rod is in its normal position, and by striking said fingers when 30 said rod is moved out of position by the friction of said wheel and brake on each other to restore said rod to its normal position, as and for the purpose specified.

In witness whereof I have signed this specification in the presence of two subscribing witnesses.

JAMES COWGILL.
